UNITED STATES PATENT OFFICE

115,064

DESIGN FOR A VANITY CAPE OR SIMILAR ARTICLE

Mathilde T. Fadie, Oakland, Calif.

Application August 23, 1938, Serial No. 79,517

Term of patent 3½ years

To all whom it may concern:

Be it known that I, Mathilde T. Fadie, a citizen of the United States, residing at the city of Oakland, county of Alameda and State of California, have invented a new, original, and ornamental Design for a Vanity Cape or Similar Article, of which the following is a specification, reference being had to the accompanying drawing, forming part thereof.

The design comprises a vanity cape of the specific contour disclosed, the raglan-type cap sleeves of which merge into the short rounded rear portion thereof and the outer edges of which are outlined with a relatively narrow border, as shown.

I claim:

The ornamental design for a vanity cape, or similar article, substantially as shown and described.

MATHILDE T. FADIE.
